(57) **CLAIM**

The ornamental design for a biological tissue sample tray, as shown and described.

DESCRIPTION

FIG. 1 is a perspective view of a biological tissue sample tray showing our new design. The transparent or translucent biological tissue sample tray is shown in a closed configuration with all lines and structures depicted.

FIG. 2 is a perspective view of the transparent or translucent biological tissue sample tray shown in a closed configuration with the lines and structures seen through the transparent or translucent upper surface not shown for clarity of illustration.

FIG. 3 is a top plan view of the biological tissue sample tray of FIG. 1. The transparent or translucent biological tissue sample tray is shown in a closed configuration with all lines and structures depicted.

FIG. 4 is a top plan view of the transparent or translucent biological tissue sample tray shown in a closed configuration with the lines and structures seen through the transparent or translucent top surface not shown for clarity of illustration.

FIG. 5 is a bottom plan view of the biological tissue sample tray of FIG. 1. The transparent or translucent biological tissue sample tray is shown in a closed configuration with all lines and structures depicted.

FIG. 6 is a bottom plan view of the transparent or translucent biological tissue sample tray shown in a closed configuration with the lines and structures seen through the transparent or translucent bottom surface not shown for clarity of illustration.

FIG. 7 is a left elevational view of the biological tissue sample tray of FIG. 1. The transparent or translucent biological tissue sample tray is shown in a closed configuration with all lines and structures depicted and the right elevational view is a mirror image.

FIG. 8 is a front elevational view of the tissue sample tray of FIG. 1. The transparent or translucent biological tissue sample tray is shown in a closed configuration with all lines and structures depicted.

FIG. 9 is a rear elevational view of the tissue sample tray of FIG. 1. The transparent or translucent biological tissue sample tray is shown in a closed configuration with all lines and structures depicted.

FIG. 10 is a perspective view of a biological tissue sample tray of FIG. 1 shown in an open configuration. The transparent or translucent biological tissue sample tray is shown with all lines and structures depicted.

FIG. 11 is a top plan view of the biological tissue sample tray as depicted in FIG. 10.

FIG. 12 is a bottom plan view of the biological tissue sample tray as depicted in FIG. 10.

FIG. 13 is a left side elevational view of the biological tissue sample tray as depicted in FIG. 10, wherein the right elevational view is a mirror image.

FIG. 14 is a front elevational view of the biological tissue sample tray as depicted in FIG. 10; and,

FIG. 15 is a rear elevational view of the biological tissue sample tray as depicted in FIG. 10.

The features depicted in broken lines do not form a part of the claimed invention.
